UNITED STATES PATENT OFFICE

ISAAC S. KEELER, OF GRAND RAPIDS, MICHIGAN, ASSIGNOR TO KEELER BRASS COMPANY, OF GRAND RAPIDS, MICHIGAN

HOOD FASTENER

Application filed February 21, 1931. Serial No. 517,437.

The main object of this invention is to provide a hood fastener which may be easily engaged and disengaged and at the same time holds the hood in closed position under substantial stress.

A further object is to provide a structure having these advantages in which the parts of the catch, except the handle, are disposed on the inner side of the hood.

10 Objects pertaining to details and economies of my invention will definitely appear from the description to follow. The invention is defined in the claims.

A structure which embodies the features of 15 my invention is clearly illustrated in the accompanying drawings in which:

Fig. 1 is a fragmentary view in section on line 1—1 of Fig. 3 of the parts of an automobile hood structure with my improvements embodied therein, the hood being shown in closed position by full lines and in partially open position by dotted lines.

Fig. 2 is a fragmentary elevation partially in section looking from the right of Fig. 1.

25 Fig. 3 is a fragmentary view partially in section on line 3—3 of Figs. 1 and 2.

Fig. 4 is a fragmentary section corresponding to that of Fig. 1 showing a modified form or embodiment of my invention.

30 Fig. 5 is a fragmentary inside view or a view looking from the left of Fig. 4.

Referring to the drawings, 1 represents an automobile hood or closure member mounted for swinging movement, 2 the jamb against

35 which it closes, and 3 a part of a vehicle body. My improved fastener or catch comprises a latch or escutcheon plate 4 which has a slot 5 therein, the closure member having a registering slot.

40 The plate 4 carries inwardly and upwardly projecting spaced catch members 6 having downwardly and outwardly inclined upper surface 6' which is the keeper-engaging part of the catch. A lever-like latching member 7 is pivoted at 8 between these members 5 so that the upper edge 9 of the latching lever lies, when the parts are in engaged position, in substantially the plane of the keeper engaging surface 6', constituting in effect an extension thereof.

The latching member 7 is provided with a handle portion 10 projecting through the latch plate. The latching member has an upwardly curved tip 11 to facilitate engagement with the keeper so that the inner end 55 of the latching member may be swung downwardly to pass through the keeper and then swung upwardly to lift and guide the keeper into engagement with the catch at the inner side of the latching member 60 pivot 8.

In the embodiment shown in Fig. 1 the keeper 12 is bail-shaped and disposed horizontally, the arms of the keeper having offset portions 13 provided with eyes to receive 65 the attaching bolts 14. The keeper is of spring or resilient material so that it engages the catch under stress when the parts are in the position shown in Fig. 1, acting not only to retain them in closed position 70 but to draw the hood or other closure inward owing to the engagement of the resilient keeper member with the inclined surface of the catch.

To release the catch the member 7 is 75 swung upwardly and at the same time the closure is drawn outwardly so that the catch may be readily withdrawn from the keeper.

In the embodiment illustrated the closure is provided with a buffer 15 for the handle portion of the member 7. The latch member may be very easily engaged and disengaged and at the same time the parts are held under substantial stress.

In the modification shown in Figs. 4 and 85 5 the keeper 16 is provided with a shank 17 slidable in a yoke-like support 18. The spring 19 is arranged on the shank in supporting engagement with the thrust member 20 and the upper end of the support 80 urges the keeper yieldingly downward. The keeper in this embodiment is mounted for swinging or rocking movement, it being held against rotative movement, however, by the thrust member 20 engaging the support 90 so that the keeper is properly positioned to be engaged by the latching member.

95 My improved fastener is very easily engaged and at the same time may be ten- 100

sioned so that the hood is not only held downwardly but is drawn inwardly, thereby effectively preventing rattling. Further, the parts are concealed so that the structure is very attractive in appearance.

To manipulate, the handpiece of the latching member may be grasped and an upward pull not only releases the latch but the handpiece may be used to manipulate the hood. The same is true in closing the hood.

I have illustrated and described embodiments of my invention which I have found very satisfactory. I have not attempted to illustrate or describe certain other embodiments or adaptations as it is believed that this disclosure will enable those skilled in the art to embody or adapt my improvements as may be desired.

Having thus described my invention what I claim as new and desire to secure by Letters Patent is:

1. In a structure of the class described, the combination with a swinging closure member, of a slotted latch plate mounted on said closure member and provided with an inwardly projecting catch having an outwardly and downwardly inclined keeper-engaging part, and a lever-like latching member pivotally mounted by means of a fixed pivot on the inner end of said catch and disposed through said slot in said latch plate, said latching member having a substantially flat keeper sliding surface and being curved upwardly at its inner end and constituting means for lifting and guiding a spring keeper into engagement with the inclined keeper engaging part of said catch as the closure member is swung to closed position, said keeper engaging said catch at the inner side of and below said latching member pivot when the parts are in latched position.

2. In a structure of the class described, the combination with a swinging closure member, of an inwardly projecting catch provided with an outwardly and downwardly inclined keeper engaging part, and a lever-like latching member pivotally mounted by means of a fixed pivot on said catch and disposed through said closure member to be manipulated from the outside thereof, said latching member having a substantially flat keeper sliding surface and being mounted on said catch to constitute a movable extension therefor for lifting and guiding a keeper into engagement with the inclined keeper engaging part of the catch at the inner side of and below the latching member pivot.

3. A structure of the class described comprising a bail-shaped spring keeper disposed horizontally, an inwardly projecting catch having an outwardly and downwardly inclined keeper-engaging part, and a lever-like latching member pivotally mounted on the inner end of said catch, said latching member being curved upwardly at its inner

end constituting means for lifting and guiding the keeper into engagement with the inclined keeper engaging part of said catch as the catch is swung to keeper-engaging position, said keeper engaging said catch at the inner side of and below said latching member pivot when the parts are in latched position.

4. A structure of the class described comprising a horizontally disposed bail-shaped spring keeper, a catch having an inclined keeper-engaging part, and a lever-like latching member pivoted upon said catch to be swung into a downwardly inclined position to disengage the keeper from the catch or to engage the latching member with the keeper, and to an upwardly inclined position to lift and guide the keeper into engagement with the inclined keeper engaging part of the catch.

5. In a structure of the class described, the combination with a swinging closure member, of a spring keeper disposed on the inner side of said closure member, an inwardly projecting catch, a lever-like latching member pivotally mounted on said catch and disposed through said closure member to be manipulated from the outside thereof, said latching member being pivoted on said catch so as to be engaged by said keeper when the closure member is in closed position, and a buffer for said latching member on the outer side of said closure reacting to the force of said spring keeper through said latching member.

6. A structure of the class described comprising an inwardly projecting catch having an outwardly and downwardly inclined keeper-engaging part, and a lever-like latching member pivotally mounted on the inner end of said catch, said latching member being curved upwardly at its inner end constituting means for lifting and guiding a keeper into engagement with the inclined keeper-engaging part of said catch as the catch is swung to keeper-engaging position, the keeper engaging said catch at the inner side of and below said latching member pivot when the parts are in latched position.

In witness whereof I have hereunto set my hand.

ISAAC S. KEELER. 115
